UNITED STATES PATENT OFFICE.

BRUNSON S. McCUTCHEN, OF NORTH PLAINFIELD, NEW JERSEY.

WRINGER.

Application filed December 18, 1920. Serial No. 431,601.

To all whom it may concern:

Be it known that I, BRUNSON S. McCUTCHEN, a citizen of the United States of America, residing at North Plainfield, in the 5 county of Somerset and State of New Jersey, have invented certain new and useful Improvements in Wringers, of which the following is a specification.

My invention relates to power wringers 10 for washing machines and has for its object to provide means whereby a parallel or uniform separation of the pressure rolls is obtained regardless of whether articles are run through the rolls centrally or at their ends.

Another object of my invention is to compensate for the increased pressure which ordinarily occurs between the rolls as the latter are separated.

A still further object of my invention is 20 to provide a simple mechanism whereby the compression between the rolls will be automatically removed when the rolls have been forced apart a predetermined distance.

A still further object of my invention is to 25 provide a common means whereby the rolls or mangle elements are maintained in parallelism and whereby the rolls are subjected to a substantially constant pressure restraining their separation.

A still further object of my invention is to 30 provide convenient manual means for "setting" the rolls to the desired compression and for conveniently releasing the same.

Other and further objects of the invention 35 will be in part obvious and in part described as the specification is proceeded with.

In the drawings forming part of this specification:

Figure 1 is a vertical sectional view partly 40 broken away through a wringer made in accordance with my invention;

Figure 2 is a section on the line 2—2 of Figure 1; and

Figure 3 is a section on the line 3—3 of

45 Figure 1.

Like reference characters indicate like or similar parts throughout the several views, in which:

A designates a substantially tubular 50 wringer frame formed with vertical side members 1 and a horizontal top member 2. Having its ends rotatably mounted in bearings 3 carried by the vertical side members is a fixed lower wringer roll 4, above which 55 is positioned an upper wringer roll 5. The upper wringer roll 5 has its ends extending

through slots 6 in the vertical side members to bearing blocks 7 movable within the vertical side members to permit a separation of the upper roll 5 with respect to the lower roll 60 in order that various thicknesses or sizes of clothes may be drained. The movable bearing blocks 7 are provided with ears 8 between which are pivotally connected as at 9 a vertically movable cross beam 10, or in 65 lieu of ears 8, the cross beam may merely bear at its ends upon the top of the respective bearing blocks. The ends of the cross beam 10 are slidably received within slotted brackets 11 secured to the frame, and the 70 under side of the horizontal portion of the frame is slotted as at 12 to permit of vertical movement of the cross beam with the upper roller. The length of the beam 10 is such as to permit of a working clearance in- 75 inside the hollow frame but prevent any end-wise movement therein. Pivoted above and to the cross beam 10 by means of corresponding pairs of links 13 is a vertically and horizontally movable cross bar 14 and it will be 80 noted that the cross beam 14 is at all times parallel with the cross beam 10. Other corresponding pairs of links 15 are pivotally secured to the frame as at 16 and to the levers 13 and cross beam 14 and form with the 85 levers 13 substantially toggle joints the purposes of which are to elevate or lower cross beam 10 and consequently the upper roller 5 upon applying force longitudinally to the upper cross bar 14. It is to be understood 90 that the relative position of the links 13 and 15 is approximately as illustrated in Fig. 1 and that as the levers more nearly approach relative alignment the upper roll is forced with increased pressure against the lower roll. The cross beam 10 serves to maintain a fixed distance between the two lower pivots of the toggle arms 13 and also to take care of any end thrust developed by the toggle 95 joints.

As a means for applying compression between the upper and lower rolls in the manner previously described, I have pivotally secured to the cross beam 14 as at 22 an inverted bifurcated scroll cam 17, which at 105 its lower end straddles the beam 14 and has secured between its upper ends as at 25, an operating handle 18, extending above the wringer frame and movable in a slot 19, provided in the frame for that purpose. The 110 scroll cam is held in an inactive position as shown in solid lines in Fig. 1 by coil springs

20, one of the ends of which engages the pin-
telle 16 to which the levers 15 are connected
and the other ends of which are connected
with a loop or bail 21 which embraces and
5 rides upon the involutely curved edge 35 of
the cam 17. As illustrated the cam 17 termi-
nates in an enlarged end 22 so that as the
same is moved through the medium of the
handle 18 as the latter is moved to dotted
10 line position, the springs are expanded and
the bail or loop 21 will slide down the in-
volutely curved edge 35 of the cam 17 and
finally engage over a shoulder 23 formed
by a bracket 24 attached to the cross-beam
15 14, it being noted that the work arm is
shortened as the spring tension increases
thereby making it possible to "cock" the
spring with a comparatively short lever.
The handle 18 can then be swung back to
20 full line position without disengaging the
bail from set or cocked position. When the
bail or loop 21 is engaged over the shoulder
23 in the manner just described the tendency
25 of the spring is to move the upper cross beam
longitudinally, or to be more exact to move
it in both a vertical and horizontal direction,
consequently tending to bring the levers 13
and 15 more nearly in relative alignment and
thereby causing the upper roller to press
30 with greatly increased pressure upon the
lower roller.

From the foregoing it will be obvious that
the bar 10 is maintained in parallelism with
the working face thereof. Therefore the
35 bearings 7 if pivotally connected with this
bar 10 will have the bearing surfaces thereof
likewise in parallelism therewith. It then
follows that if a relatively thick wad of
clothing is inserted at one end of the rollers
40 causing a sudden rise of the corresponding
end of the roller 5 the entire pressure of
spring 20 will bear against this end
causing the opposite or remote end to
45 elevate until it engages its bearing
with sufficient force to counter-
balance the force at the end of roller at
which the clothing has been introduced. As
the working face of the roller or mangle
50 element 5 at this time parallels the working
faces of the bearings 7 the working face of
the roller 5 is parallel to the working face
of the roller 4. It will be understood that
the foregoing is merely a description of the
theory upon which the operation of the roller
55 5 is based. In actual practice the elevation
of the remote end of the roller is simultane-
ous with the elevation of the end at which
the wad of clothing has been introduced.
The mechanism illustrated by parts 7 to 16
60 and 20 therefore constitutes means for main-
taining the working faces of the mangle ele-
ments in parallelism. It will likewise be
understood that the operation of the roll 5
as above set forth is that occurring under
65 abnormal conditions brought about mainly

by careless and unskilled handling. Under
normal conditions when the clothing passing
through the rolls is evenly distributed the
pressure exerted upon the ends of the roll
5 will be equal and constant. 70

Should the operator desire to relieve the
pressure between the rolls, she merely strikes
the handle 18, depressing the same from its
full line position to a point adjacent or
touching the frame, whereupon the enlarged 75
end 22 of the cam lifts the bail 21 from the
shoulder 23 and the pressure exerted by the
upper roller upon the lower roller is im-
stantly relieved and the rolls are in conse-
quence free to separate. 80

In order to insure the automatic release of
the compression when the rolls have been
forced apart a definite predetermined dis-
tance, as when the operator gets her hand
caught, I attach to the lower cross beam 10 85
a finger or detent 34 which engages the loop
21, forcing the latter upwardly over the
shoulder 18 upon movement of the upper
roller 5 to approximately its extreme up-
ward position, thus automatically releasing
90 the springs and eliminating the pressure be-
tween the rolls. As will be noted from the
drawings, the finger or detent 34 comprises
a strap of sheet metal or the like embracing
the beam 10 with its spaced ends in straddling
95 relation with the enlarged end of the cam
lever 17. It will of course be understood that
as the detent moves upwardly as the rolls
separate, that the cross bar 14 is simultane-
ously moved upwardly and longitudinally or
endwise to the right (Fig. 1) until the end
of loop 21 is brought into proper position
to be engaged by the detent or finger 34.

As the rolls are forced apart in actual
practice, due to increased thickness of clothes
being passed between them the angles be-
tween the arms of the toggle joints, 13 and
15, decrease and thereby tend to decrease
the pressure upon the upper roll at a rate
which changes in proportion to twice the tan-
gent of half the above named angle. At the
same time the helical springs are elon-
gated. This tends to increase the pressure
upon the upper roll at a rate approximately
in proportion to the elongation of said
springs. Since one force is decreasing
while the other is increasing, an approxi-
mately constant pressure is maintained upon
the upper roll, when the amount of separa-
tion between the rolls lies within the limits 120
required for practical operation of a clothes
wringer. It will be seen that the mechanism
illustrated by the parts 7 to 16 and 20 com-
prises likewise a means for imposing upon
the movable roll or mangle element 5 an ap-
proximately constant pressure and is ac-
cordingly a common means for maintaining
the mangle elements in parallelism and im-
posing upon the movable mangle element an
approximately constant pressure. 125

Attention is directed to the fact that while pressure upon the two ends of the roll or mangle element 5 may be unequal under abnormal conditions the total pressure exerted on the roll 5 to urge it toward the roll 4 is approximately constant.

From the foregoing it is believed that both the operation and the theory of operation of the present wringer will be readily understood by one skilled in the art, but it is pointed out that with power wringers of the conventional type the unevenness or varying size of the "load" often completely renders the wringer inapt for use, while in the present wringer not only is the pressure between the rollers positively regulated by the automatic release but also all undue strain such as would be caused if suddenly a large wad of clothing was passed between the rollers is prevented.

While in the foregoing I have shown and described the preferred embodiment of my invention I desire it to be understood that the privilege is reserved to make such changes in construction, combination and arrangement of parts as fall within the scope of the subjoined claims.

What I claim is:

1. A wringer comprising a fixed roller and a movable roller, bearing members for the movable roller, a cross beam connecting the bearing members, means for exerting a pressure against the movable roller for moving the movable roller toward and away from the fixed roller, said means including a longitudinally movable equalizing beam spaced from but connected with the cross beam.

2. A power wringer comprising a fixed roller and a movable roller, a cross beam carried by the movable roller, an equalizing beam connected with the cross beam, a cam and cam actuated member for throwing the equalizing beam to cause downward pressure to be uniformly applied to the ends of the movable roller, means for maintaining the cam actuated member in operative position and means carried by the cross beam for automatically moving the cam actuated member to inoperative position.

3. A power wringer comprising a fixed roller, a movable roller, means for restraining the separation of the rollers, means associated with the first mentioned means for maintaining the pressure between the rollers constant under normal conditions, and means for automatically releasing the last mentioned means upon upward movement of the movable roller.

4. A power wringer comprising a frame, upper and lower relatively movable pressure rolls mounted in said frame, a cross beam carried by one of said rolls, a second cross beam, link bars connecting said beams to the frame and to each other in spaced par-

allel relation and means for actuating said second beam and said link bars to force said beams apart in a lateral direction.

5. A power wringer comprising a frame, upper and lower pressure rolls mounted in said frame, said upper roll capable of moving toward and away from said lower roll, means for restraining the separation of said rolls comprising a cross beam mounted for vertical movement in said frame but locked against endwise movement, means for connecting said beam with said upper roll, a second cross beam, link bars connecting said beams together, other link bars connecting said first mentioned link bars to the frame, a cam lever pivoted to said second cross beam, and a coil spring connected at one end to said frame and at its other end to said second cross beam, for the purpose described.

6. In a wringer, a pair of mangle elements one of which is movable; means for forcing the movable mangle element toward the other of said mangle elements, including a shiftable bar, links connecting said bar to the wringer frame, a spring engaging said bar to shift the same in one direction, and an operative connection between said bar and said movable mangle element, whereby said movable mangle element is moved toward said stationary element when the bar is moved by said spring; and means actuated by the movement of said movable mangle element in a direction away from the stationary mangle element for disengaging said spring from said bar.

7. In a wringer a stationary roll, a movable roll, means for resiliently forcing the movable roll toward said stationary roll, said means including a shiftable member and links connecting said shiftable member to the frame and to the movable roll, a spring normally engaging said shiftable member, and means for automatically releasing said spring from said shiftable member when said movable roll has been separated from said stationary roll a predetermined distance.

8. In a wringer a stationary roll, a movable roll, means for resiliently forcing the movable roll toward said stationary roll, said means including a shiftable member, and links connecting said shiftable member to the frame and to the movable roll, a spring normally engaging said shiftable member, means for automatically releasing said spring from said shiftable member when said movable roll has been separated from said stationary roll a predetermined distance, and manual means for releasing said spring from and reengaging said spring with said shiftable member.

In testimony whereof I affix my signature.

BRUNSON S. McCUTCHEON,
